UNITED STATES PATENT OFFICE.

ALVA VINCENT CAMPBELL, OF CROYDON, ENGLAND, ASSIGNOR OF ONE-HALF TO JOSEPH LAMBERT, OF SAME PLACE.

BOOT OR SHOE PROTECTOR.

SPECIFICATION forming part of Letters Patent No. 585,554, dated June 29, 1897.

Application filed April 1, 1896. Serial No. 585,763. (No model.) Patented in England January 29, 1896, No. 2,104, and in France March 5, 1896, No. 241,799.

To all whom it may concern:

Be it known that I, ALVA VINCENT CAMPBELL, a subject of the Queen of Great Britain and Ireland, residing at 44 Tamworth Road, 5 Croydon, in the county of Surrey, England, have invented certain new and useful Improvements in Boot or Shoe Protectors, of which the following is a specification.

The invention has been patented in Eng- 10 land, No. 2,104, dated January 29, 1896, and in France, No. 241,799, dated March 5, 1896.

This invention is designed to prevent the wearing down of the heels of boots and shoes and is applicable to new boots or for the re- 15 pair of old ones.

Referring to the drawings which form part of this specification, Figure 1 shows a plan view of the top of a boot-heel fitted with my protector, and Fig. 2 shows a vertical section 20 of same on the line *xx*.

a is the triangular flat piece of leather or metal, which forms the protector and the sides of which are curved to the shape of the heel.

b is a screw by which the plate *a* is fas- 25 tened to the heel. This screw should be well sunk in to prevent the head from wearing away.

d d are short pins, which may be cast on the protector on the upper surface of plate *a* to prevent same shifting when fixed.

e is a narrow curved plate which serves, first, to help to lock the plate *a* in position, and, second, to complete the half or three-quarter curve of the heel on the wearing side.

35 This plate *e* is fixed in the usual way. It is entirely optional.

The method of use is easily understood. The protector is fixed level with the top piece and fastened down by the center screw. The pins prevent lateral movement until the screw 40 is withdrawn, when the protector can be lifted and its sides transposed. The side piece is fastened down by screws or nails level with the top piece and three-sided protector.

This invention will prevent that frequent 45 cause of injury to boots and shoes (overrun heels) which often results in sprained ankles. It is applicable to all kinds of boots and shoes. When made of leather or other fibrous material, it is by preference furnished with a row 50 of nails or plugs on its edges. It can be made of leather or any suitable metal or material and may be waterproofed or compressed, or, if metal, coated with copper or zinc to prevent oxidation.

Having now described my invention, what I claim, and desire to secure by Letters Patent, is—

In combination, in a heel-protector, a plate *a* having a plurality of wearing edges, a screw 60 for holding the plate and allowing it to be ad- justed to bring either of its edges in proper position and the wear-plate *e* extending along one edge of the heel and having its end fitted against the edge of the adjustable plate, sub- 65 stantially as described.

In witness whereof I have hereunto set my hand in presence of two witnesses.

ALVA VINCENT CAMPBELL.
